SHADE ROLLER CHECK

James M. Wilson, Newark, N. J., assignor, by
mesne assignments, to Shade Check, Inc.,
Newark, N. J., a corporation of New Jersey

Application December 15, 1936, Serial No. 115,897

3 Claims. (Cl. 156—36)

This invention relates particularly to spring actuated window shade rollers, and more especially to a check for preventing rotation of the roller under the influence of the spring at a speed in excess of a predetermined limit, for example when a shade escapes from the hand of the person raising or lowering the shade. However, the invention is equally susceptible to other types of spring operated rollers.

One object of the invention is to provide a novel and improved check of the nature described which shall include a part carried by the roller to engage a stationary member, for example a shade bracket, said part normally permitting free rotation of the roller in raising or lowering the shade, in combination with means carried by the roller and actuated by centrifugal force caused by rotation of the roller at an excessive speed to positively engage said part so as to stop rotation of the roller.

Another object is to provide such a check which can be utilized in connection with many different types of spring operated rollers and many different types of stationary supports or roller brackets, and which can be easily and quickly applied to the end of a roller opposite the usual controlling pawls and ratchets so that the unit can be supplied to users of shade rollers for application to rollers already in use.

Other objects are to provide a spring roller check of the character described which shall include a pawl and ratchet mechanism carried by the roller and including cooperating parts, one of which is adapted to engage a stationary support, for example a shade bracket, while the other is movably mounted on the roller and subject to actuation by centrifugal force, said pawl and ratchet being normally disengaged from each other to permit free rotation of the roller in both directions at normal speed and being forced into interlocking engagement upon rotation of the roller at excessive speed under influence of the roller spring so as to stop rotation of the roller; and to obtain other advantages and results as will be brought out by the following description.

Referring to the accompanying drawing in which corresponding and like parts are designated throughout the several views by the same reference characters,

Figure 1 is a top plan view of a shade roller installed in brackets and having a check embodying my invention applied thereto.

Figure 2 is an end view of the roller and shade bracket on the line 2—2 of Figure 1.

Figure 3 is an enlarged fragmentary sectional view on the line 3—3 of Figure 1.

Figure 4 is a sectional view on the line 4—4 of Figure 1.

Figure 5 is a sectional view on the line 5—5 of Figure 2 showing the pawl and ratchet tooth in normal disengaged relation.

Figure 6 is a horizontal sectional view on the line 7—7 of Figure 1.

Figure 7 is a view similar to Figure 6 showing the pawl in engagement with the ratchet tooth to stop rotation of the roller, and

Figure 8 is a fragmentary plan view of one end of a shade roller showing a modification of the invention.

Specifically describing the invention, the reference character A designates a spring operated shade roller of known construction having the usual controlling pawl and ratchet mechanism B at one end, a fixed shaft C and a trunnion D at 20 its opposite ends mounted in stationary supports or brackets E. Within the roller is the usual spring for normally rotating the roller in one direction, for example to wind the shade thereon, the spring being tensioned or wound by rotation 25 of the roller in the other direction as in lowering the shade.

At the end of the roller opposite the controlling pawls B is the check embodying my invention. This check is shown as including a casing 30 G including a cup-shaped section 1 and a cover plate 2. Preferably, although not necessarily, the edge of the section 1 has a plurality of lugs 3 fitted in notches 4 in the cover plate for securing the cover plate on the cup-shaped section 1. 35

The casing is secured to the end of the roller by the rotatable trunnion D which as shown preferably includes a pointed shank 5 to be driven into the roller, and a bearing portion forming a shoulder 7 between itself and the shank 5. At 40 the end of the bearing portion 6 opposite the shoulder 7 is a collar 8, and outwardly of the collar is a trunnion portion 9 to fit the opening in the corresponding bracket E. The shank of the trunnion D passes through an opening in the 45 center of the bottom of the section 1 of the casing so that the casing is clamped between said shoulder and the end of the roller. Preferably a nail or like fastener 11 also passes through openings 12 and 13 in the cover plate and section 1 and is driven into the roller to hold the casing against rotation.

Rotatably mounted on the bearing portion 6 of the trunnion is a ratchet sleeve 14 which has a ratchet tooth 15, one end of the sleeve project- 55

ing through an opening 150 on the cover plate and being riveted to the shank 16 of a stop member which has a laterally projecting end 17 to engage the shade bracket E. The ratchet sleeve 14 and stop member 17 are normally freely rotatable on the trunnion D, although a complete revolution of the sleeve and stop member is prevented by engagement of the stop member with the top or bottom of the shade bracket, as shown, 10 for example in Figure 2.

Cooperating with the ratchet sleeve 14 is a pawl 18 pivotally mounted intermediate its ends on a pin 19 secured in the casing section I. One end of the pawl 18 is counterweighted at 20, and 15 a leaf spring 21 is interposed between the pawl and the casing section I so that the pawl is normally held out of engagement with the ratchet tooth 15 during rotation of the roller at normal speed as when raising and lowering the window 20 shade, for example as shown in Figure 5, while when the roller is rotated at a greater than normal speed or in excess of a predetermined speed under influence of the roller spring, the centrifugal force set up by rotation of the roller will 25 swing the pawl 18 into engagement with the ratchet tooth 15, as shown in Figure 7.

When the pawl and ratchet tooth are disengaged as shown in Figure 5, the roller may freely 30 rotate in either direction at normal speed. However, the ratchet tooth is so related to the direction of rotation of the roller that when the roller is rotated at a greater than normal speed or in excess of a predetermined speed under influence of the spring in one direction, as upon escape of 35 the shade from the hand of the person adjusting it, the centrifugal force set up by rotation of the roller will swing the pawl 18 into engagement with the tooth 15, as shown in Figure 7, which will in turn cause rotation of the sleeve 14 and 40 stop member so that the laterally extending end 17 of the stop member will engage the shade bracket 8 and stop further rotation of the roller in the same direction. Obviously the roller may be rotated in the other direction, as in unwinding 45 the shade, at any desired speed without interference by the pawl and ratchet check.

If desired, the stop member 16, 17 may be fastened against movement to the bracket E or other stationary member, such as the window 50 frame.

In Figure 8 is shown a modification wherein the shade roller is mounted in another form of bracket 22 which has a notch 23 at one edge in which the stop member 17 is inserted. The 55 bracket 22 is thereby permanently engaged by the stop member 17, the structure for stopping "running away" of the roller being otherwise the same as hereinbefore described.

It will thus be seen that the invention provides 60 a reliable, simple and inexpensive check to prevent "running away" of the spring operated roller under the influence of the spring and the check constitutes a unit which may be applied to different rollers and in connection with different 65 types of shade brackets without modification of the roller or the brackets.

While the forms of the invention herein described are the now preferred forms, it should 70 be understood that they are primarily for the purpose of illustrating the principles of the invention and that many modifications and changes may be made in the details of structure without departing from the spirit or scope of 75 the invention.

Having thus described my invention, what I claim is:

1. The combination with a spring actuated roller, of means for checking the roller upon rotation thereof under influence of its spring at a speed in excess of a predetermined limit, said means including a stationary member adjacent but spaced and separate from one end of the roller, a casing including a cup-shaped section having a central opening in its bottom, a trunnion pin fitted coaxially in said end of the roller and having a shoulder engaging the bottom of the casing to clamp the casing between itself and the end of the roller, a ratchet sleeve having a tooth mounted on said pin outwardly of said shoulder for relative rotation coaxially therewith and having a lateral projection adapted in one position to engage said stationary member, and a pawl pivoted on said casing to cooperate with said ratchet tooth and normally disengaged 20 therefrom to permit rotation of said roller under influence of the roller spring at speeds below said limit, said pawl being actuated by centrifugal force into engagement with said tooth and said ratchet sleeve being thereby rotated to cause engagement of said lateral projection with said stationary member upon rotation of said roller at excessive speed to stop rotation of the roller.

2. The combination with a spring actuated roller, of means for checking the roller upon rotation thereof under influence of its spring at a speed in excess of a predetermined limit, said means including a stationary member adjacent but spaced from one end of the roller, a casing secured coaxially on said end of the roller, a pin 30 through and coaxial with said casing and freely rotatable relative to said stationary member, a ratchet sleeve having a tooth mounted on said pin within the casing for relative rotation coaxially therewith and having a portion projecting from said casing and adapted in one position to engage said stationary member, and a pawl pivoted in said casing to cooperate with said ratchet tooth and normally disengaged therefrom to permit rotation of said roller under influence of the roller spring at speeds below said limit, said pawl being actuated by centrifugal force into engagement with said tooth and said ratchet sleeve being thereby rotated to cause engagement of said projecting portion with said stationary member upon rotation of said roller at excessive speed to stop rotation of the roller.

3. The combination with a spring actuated roller, of means for checking the roller upon rotation thereof under influence of its spring at a speed in excess of a predetermined limit, said means including a stationary member adjacent but spaced from one end of the roller, a pin on said end of said roller coaxial therewith and freely rotatable with respect to said stationary member, a part on and rotatable relatively to said pin and having a portion projecting from said end of the roller and adapted in one position to engage said stationary member, and a second part pivotally mounted on said roller to cooperate 60 with said first part and normally disengaged therefrom to permit free rotation of said roller under influence of the roller spring at speeds below said limit, said second part being actuated by centrifugal force into engagement with said first part and said first part being thereby actuated into engagement with said stationary member upon rotation of the roller at excessive speed to stop rotation of the roller.

JAMES M. WILSON. 75
